WINTHROP K. HOWE, OF ROCHESTER, NEW YORK, ASSIGNOR TO GENERAL RAILWAY SIGNAL COMPANY, OF GATES, NEW YORK, A CORPORATION OF NEW YORK.

AUTOMATIC TRAIN-CONTROL SYSTEM.

1,405,377.

Specification of Letters Patent. Patented Jan. 31, 1922.

Application filed July 3, 1916, Serial No. 107,357. Renewed June 25, 1921. Serial No. 480,462.

To all whom it may concern:

Be it known that I, WINTHROP K. HOWE, a citizen of the United States, and a resident of the city of Rochester, in the county of 5 Monroe and State of New York, have invented new and useful Improvements in Automatic Train-Control Systems, of which the following is a specification.

This invention relates to automatic train control systems and more particularly to 10 such systems which act to control the speed of the train.

In my prior application, Serial No. 38,132, filed July 6, 1915, I have disclosed 15 a system for automatically controlling the speed of railway trains, in which, generally stated, the speed of the train is controlled by the co-operation of a device thereon indicating the actual speed of said train with 20 another device, specifically a rotary cam, which is moved in accordance with the distance traveled by the train and which indicates the permissive speed for the train at each point in its travel, said cam being arranged 25 to be connected to a pair of wheels of the train by means of suitable gearing. In view of the important duty performed by this gearing, it is desirable to make provision for checking its integrity, and the primary 30 object of this invention is a construction and arrangement of parts whereby each time the speed control apparatus is so controlled as to connect the cam above mentioned to the wheels of the vehicle, it is necessary 35 for this gearing to be intact and operating properly in order to permit the vehicle to proceed.

Other objects and advantages will appear 40 as the description of the invention progresses, and the novel features of the invention will be particularly pointed out in the appended claims.

In describing the invention in detail, reference is had to the accompanying drawing, 45 wherein I have illustrated a preferred physical embodiment of my invention, and wherein like characters of reference designate corresponding parts throughout the several views, and in which:

50 Figure 1 is a diagrammatic view, partly in the nature of the wiring diagram, which shows the parts and electric circuits constituting one form of the invention, said parts being illustrated more with a view of making 55 their functions and operation clearly

understood than with regard to their exact construction and arrangement; and

Fig. 2 is a fragmentary view showing some of the parts shown in Fig. 1, Fig. 2 being a section taken substantially on the line 2—2 in Fig. 1.

Referring to the accompanying drawing, the numeral 1 designates a portion of a track rail of the ordinary railroad track upon which the wheels of the vehicle run; and for simplicity only one of the wheels upon which the vehicle is supported is shown, this wheel 2 being connected to the usual axle 3. According to the preferred embodiment of the invention illustrated in the accompanying drawing communication between the track and the vehicle necessary for the operation of the train control system is obtained by the mechanical and electrical co-operation of a contact shoe carried by the vehicle with ramps or contact rails located at intervals along the track. The contact shoes may be of any suitable construction; and for simplicity are shown diagrammatically in the accompanying drawing as comprising a vertically movable plunger 5, slidably mounted in a bracket 4 carried by the vehicle, said bracket 4 for simplicity being assumed to be made of suitable insulating material. The shoe or plunger 5 is provided with a suitable foot or enlargement at its lower end which constitutes the ramp-engaging portion thereof; and said shoe is pressed downward to its lower position, shown in Fig. 1, by a compression spring 7 interposed between a collar 6 fixed to said shoe and the under face of the bracket 4. The shoe 5 is designed to open a circuit when lifted, and to perform this function is shown provided with a button 8 of insulating material, which is larger than the stem portion of said shoe, and which is adapted to form a stop for limiting the downward movement of said shoe; and this button 8 is arranged to lift a contact spring 9 out of 70 electrical contact with a contact piece 10 when said shoe is lifted.

The ramp with which the shoe 5 engages may be of any suitable construction and in general comprises a metallic contacting portion having sloping ends which is supported on any suitable insulating supports adjacent to one of the track rails so as to extend substantially parallel therewith and in the plane of the contact shoe. The electrical co- 105

operation of the contact shoe 5 with the ramp R, utilized for controlling the automatic train control system, is due to the electrical contact of said shoe with the metallic 5 contacting portion of said ramp, during which a partial circuit on the vehicle, hereinafter pointed out, is connected to one of the partial circuits including a source of current which is associated with said ramp, so 10 that electrical energy may be transmitted from the ramp to the vehicle, subject to proper control in accordance with traffic conditions. The partial circuits associated with the ramp R may be of any suitable arrangement, and it is contemplated that these partial circuits will be controlled by the track relays of certain track circuit sections into which the railroad track is divided in the usual manner; but, for simplicity, 15 these trackway circuits are not shown. The source of current associated with the ramp R is shown as comprising a transformer T, the primary 11 of which is connected to a transmission line or an alternating current 20 generator of suitable construction. One terminal of the secondary 12 of the transformer T is connected by a conductor 13 to the track rail 1 and the other terminal of said secondary is connected by conductor 25 14, switch 15 and conductor 16 to the ramp R. It is apparent that this simplified arrangement provides a means for establishing a difference of potential between the track rail 1 and the ramp R equivalent to the 30 voltage of the secondary 12, and for discontinuing this difference of potential by opening the switch 15.

The parts of the speed control apparatus are preferably in practice suitably supported in a box or casing F, a part of which is shown in the accompanying drawing, and affords a convenient means for supporting the various parts of the speed control apparatus.

45 The essential parts of the speed control apparatus are illustrated diagrammatically in the accompanying drawing, and included in these parts is a speed indicator SI, which is connected to and driven by the wheels of 50 the vehicle, and is so constructed as to indicate, by the movement given to a part or member, the changes in the speed of the vehicle. In the simplified construction illustrated, a worm 17 is fixed to the axle 3, 55 and meshing with said worm 17 is a worm gear 18 which is secured to the lower end of a shaft 19, said shaft 19 being journaled in suitable supports 20 and being provided with collars 21 pinned thereto, which are 60 disposed above and below said supports 20 and serve to prevent endwise movement of said shaft 19. Fixed to the shaft 19 by a pin 23 is a block 22; and loosely mounted on the shaft 19 below the block 22 is another 65 block 24. Connected to the ends of the block

22 are links 25 which are also pivotally connected to weighted balls 26; and, similarly connecting the block 24 to said balls 26 are links 27. A compression coil spring 28 is interposed between the two blocks 22 70 and 24. Journaled in any suitable supports (not shown) is a shaft 30 to which is keyed an arm 31 having its free end bifurcated; and supported by the bifurcated ends 32 of said arm are freely revoluble rollers 33, 75 which are disposed between flanges 29 secured to or integral with block 24 of the speed indicator SI. The operation of the speed indicator SI is similar to that of the well known governor used for controlling the speed of engines, and will be readily apparent without further explanation.

The device for indicating the permissive speed for the vehicle at different points in its travel, which comprises a cam, is also 85 connected to the wheels of the vehicle, and in the arrangement shown in the drawing this connection comprises a beveled gear 34 fixed to the shaft 19, which meshes with another beveled gear 35 fixed to the end 90 of a shaft 36, which is supported in suitable bearing brackets or lugs 37 integral with or secured to the frame or casing F, said shaft 36 being provided with collars 38 pinned thereto and disposed on opposite sides of the 95 brackets 37, so as to limit the endwise movement of said shaft 36. Fixed to the shaft 36 is a worm 39, which meshes with a gear 40 journaled on a bearing stud or pin 41 fixed to the casing F. A small gear 42 fixed 100 to the gear 40 is also journaled on the pin 41 and meshes with the larger gear 43 journaled on a pin 44 also secured to the casing F; and fixed to the gear 43 is a small gear 45 which meshes with a larger gear 46. In 105 a similar way intermeshing gears 47, 48 and 49 are journaled on bearing studs 50 and 51, and serve to complete a train of gears which will be readily recognized as the well known reduction gearing. Journaled at one end on 110 the pin 51 is a lever 52 to which are rigidly fixed two pins 53 and 54; and mounted on said pins are two intermeshing gears 55 and 56, the gear 56 being also in mesh with the gear 49.

115 Disposed above the outer or free end of the lever 52 is a cam control magnet C comprising two coils 57, the pole pieces of which are connected at their lower ends by the usual yoke 58, said yoke being bolted to lugs 120 59 integral with a wall of the casing F. The armature 60 of the cam control magnet C is guided by pins 61 secured in the pole pieces of the coils 57; and this armature 60 is rigidly connected to a rod 62 which extends downwardly through an opening in the yoke 58 and is pivotally connected to the outer or free end of the lever 52. A collar 63 is securely fastened to the rod 62, as by a pin, and interposed between the collar 63 125 130

and the yoke 58 is a compression coil spring 64 which tends to move the rod 62 and the lever 52 to their upper position opposite to the position shown in Fig. 1.

- 5 Journaled at one end in a boss 65 integral with one wall of the casing F is a cam-shaft 66 to which is pinned a gear 67, having a small semi-circular portion cut out of its periphery as indicated by the numeral 68.
- 10 The gear 67 is disposed in the same plane as the gears 55 and 56, hereinbefore described, and is arranged to be driven by said gears at times when the lever 52 is in its upper position. Securely fastened to the cam-shaft 15 66, as by being pinned thereto, is a cam-shaped plate, hereinafter termed the cam 69. The factors determining the shape of this cam 69 will be pointed out more fully hereinafter. Also rigidly fastened to the cam-shaft 20 66, as by a pin, is an arm 70, the outer end of which is rounded and fits in a yoke formed by two fingers 71 on the outer end of one arm of an angle lever L, which is journaled on a stud or pin 72 integral with 25 the casing F; and the other or vertical arm 73 of the angle lever L is arranged to make electrical contact with curved contact strips or segments 74, which are disposed on opposite sides of said arm 73 with a slight space 30 between them.

From the construction so far described it can be seen that a part of the system, namely, the shaft 30, is so arranged and connected that it assumes different positions or is 35 placed in accordance with the actual speed of the vehicle, and that another part, comprising the cam 69 and the cam-shaft 66, is so arranged and constructed that it may be moved at times in accordance with the travel 40 of the vehicle, and may be used to indicate the permissive speed for the vehicle at each point as determined by the shape of the cam 69. As indicated hereinbefore, the speed of the vehicle is controlled by the cooperation 45 of the part which indicates the actual speed of the vehicle and of the part which indicates the permissive speed for the vehicle; and this cooperation may be attained in different ways and may be utilized to act upon 50 the brakes or other means used for controlling the movement of the vehicle. In the construction and arrangement of parts illustrated, an arm 75 is fixed to the shaft 30 and extends downwardly below the cam-shaft 55 66; and pivotally connected to the lower end of said arm 75 is the lower end of a floating lever 76, the upper end of which is provided with a freely revoluble roller 77 arranged to bear against the edge of the cam 69. A link 60 78 is pivotally connected at one end to the middle point of the floating lever 76, and at its other end to an arm 79 secured to a contact sector 80, which is journaled on a suitable shaft 81 supported by the frame or casing F. Integral with the casing F is a

horizontal lug or bracket 82, which supports upper and lower contact carrying blocks 83 and 84 of suitable insulating material; and supported by the blocks 83 and 84 are two contact supports 85 of the same construction which support contact fingers 86 and 91 and which also serve as binding posts. The contact finger 86 is formed with a pair of ears 87, which are connected by a horizontal pin 88 to one of the contact supports 70 85, this construction supporting the contact spring 86 so that it may be rocked in a vertical plane. The contact finger 86 is pressed in one direction, toward the left as viewed in Fig. 1, by a compression spring 89, 80 mounted upon a pin secured to the corresponding contact support 85 in an obvious manner. Fixed to the left hand face of the contact spring 86 is a freely revoluble roller 90 of insulating material, which is arranged 85 to bear against the outer edge of contact sector 80, as clearly shown in Fig. 1. The contact finger 91 is supported on the other contact support 85 in the same way as hereinbefore described in connection with the contact 90 finger 86.

Normally, when the parts are in the position shown in Fig. 1, the contact finger 86 is moved some distance to the right from its contact support 85 against the opposition of 95 the spring 89, while the contact finger 91 is moved only a short distance from its contact support 85; and it is apparent that if the contact finger 86 were allowed to move to the left, said contact fingers would separate, 100 since the contact finger 91 could move only a very short distance as compared with the contact finger 86.

The outer edge of the contact sector 80 is formed with a cutaway portion, leaving a 105 shoulder 92. A tension spring 93 is connected at one end to the arm 79 and is anchored at the other end to the insulating block 83.

The cam-shaft 66 is provided with an appliance for restoring it to its initial position after it has been turned by the gearing connecting it to the wheels of the vehicle. As shown, this appliance comprises an arm 94 journaled at its upper end on a pin or 110 shaft 95, which is supported in lugs 96 integral with the top of the casing F, and this arm 94 is formed at its lower end with a toothed sector which meshes with a pinion 97 fixed to the cam-shaft 66. Also journaled 115 on the shaft 95 are two blocks 98, which are held against endwise movement by a small pin 99 extending through the shaft 95; and integral with the upper end of the arm 94 is a laterally extending foot or lug 100, 120 which is arranged to strike either of the blocks 98 as the arm 94 is rocked in one direction or the other. Extending loosely through each block 98 is a rod 101, the upper 125 end of which is pinned to a boss 102, inte- 130

gral with the top of the casing F; and encircling each rod 101 is a compression coil spring 103, one end of which presses against the corresponding block 98, and the other end of which bears against a washer or collar 104 held in place on said rod 101 by a small transverse pin 105 extending therethrough.

According to the embodiment of the invention shown, it is contemplated that the speed of the vehicle will be retarded by the ordinary and well known system of air brakes; but since this system of brakes is well known in the art, no attempt has been made to show the construction and arrangement of its parts in detail. To better illustrate the application of the train control system embodying this invention to this system of air brakes, however, there is shown a portion 106 of the usual train pipe included in said system of brakes together with a valve of simplified construction for opening communication between this train pipe and the atmosphere, and it is sufficient for a clear understanding of this invention to know that the opening of this valve and the venting of the train pipe 106 automatically causes an application of the brakes. As shown, the valve above mentioned comprises a casing 107, through which extends a plunger or rod 108, the lower end of said plunger 108 being formed with a valve 109 adapted to make an air tight joint with a suitable valve seat. Within the casing 107 is a compression spring 110, which bears against the valve 109 and tends to move it to its open position, whereby there is established the free communication between the train pipe 106 and the atmosphere which causes the application of the brakes. The upper end of the rod 108 constitutes the core or plunger of a solenoid E, which, according to the arrangement of controlling circuits shown and hereinafter described, is arranged to be normally energized so as to hold the valve 109 against its seat.

The speed control apparatus is governed electrically by a relay SC carried on the vehicle and hereinafter termed the speed control relay; and this relay SC is provided with two armatures or contact fingers 111 and 112, which are illustrated conventionally. The relay SC is in turn controlled by another relay P carried on the vehicle, and hereinafter termed the pickup relay, and the relay P is provided with one armature 113.

Associated with the speed control apparatus and constituting one of the important parts of the improvement embodying this invention is a circuit controller K, which is so constructed and arranged as to be operated electrically and to open after its controlling circuit has been broken and after the lapse of a predetermined time.

This circuit controller K is shown in the accompanying drawing in a simplified form as comprising a rod or plunger 114, to which is secured and insulated therefrom a contact block or disk 115, said contact disk 115 being arranged to make electrical contact with a pair of contact springs 116 for a portion of the movement of said plunger 114. The upper end of the plunger 114 constitutes the core of a solenoid 117; and the lower end of said plunger is connected to a piston 118 which is provided with a flexible packing and which is disposed within a dashpot cylinder 119 having a small hole 120 in its lower end. The parts of the circuit controlling device K are shown in Fig. 1 in the normal position corresponding to the position which the parts assume when the controlling circuit for the solenoid 117 is closed, and in which the contact disk 115 makes contact with the contacting springs 116; and it will be readily apparent that when the solenoid 117 is deenergized, the plunger 114 will fall gradually by its own weight, at a rate determined by the rapidity of the escapement of the air from the dashpot cylinder 119 through the hole 120; and that after the lapse of a predetermined time, depending upon the weight of the parts and the size of the hole 120, the plunger 114 will move downward to the point where the contact disk 115 moves out of electrical contact with the contact springs 116.

In order to provide the necessary electric current for operating and controlling the parts of the speed control system carried on the vehicle, a suitable source of current, herein shown as comprising two batteries A and B, is carried on the vehicle; but it is obvious that a single battery, motor generator or other source of current may be used, if desired.

To determine the shape of the cam 69 involves a determination of the factors 110 which affect the braking distance of the particular railroad equipment with which the cam 69 is associated, and which are dependent on the particular physical characteristics of the railroad over which the vehicle travels. The braking distance above mentioned for a railroad train is the distance in which that train may be brought to a stop by its brakes, and, as is clearly understood by those skilled in the art of 115 braking trains, this distance not only depends upon the kind of braking equipment, but also upon the speed of the train at the time the brakes are first applied, upon the grade of the track over which the train is 120 traveling while being stopped, the curves of this stretch of track, and other factors characteristic of this stretch of track which affect the retarding effect of the brakes. It is possible to determine what is known as 130

the braking curve for a train when a particular kind of braking equipment and a given stretch of track are assumed, and this braking curve is a speed-distance curve

5 which represents for each point in the travel of the train, while its brakes are applied, what the speed of said train will be at that point. In other words, this braking curve shows how fast a train can be moving at a 10 given point in its travel over the assumed stretch of track, and yet be brought to a stop by its brakes before another predetermined point is reached. The shape of the cam 69 is determined from the braking 15 curve of the train upon which this cam is mounted with reference to a certain stretch of track having a particular grade, curves, or the like. For instance, the cam 69 may be shaped to conform to the braking curve 20 of the train for a level and straight stretch of track of a certain length. In practice, however, the different stretches of track or blocks, through which it is necessary to control the speed of the train, will not be of 25 the same length, nor of the same grade, nor will their other physical characteristics, such as curves, be the same; and if it is desired, to control the speed of the train in these several blocks precisely in accordance 30 with the braking curves of the train for these several blocks, it is apparent that it will be necessary to have a number of cams. For this reason it is contemplated according to this invention that a plurality of 35 cams will preferably be used in the manner and for the reasons fully explained in my prior application above mentioned; but since this use of more than one cam forms no part of the present invention, there has 40 been shown only one cam.

In the particular kind of cam illustrated, the lengths of the radii of said cam represent different speeds, and the angular displacement of said cam from its initial position, as shown in Fig. 1, represents the different distances traveled by the train after the cam commences to move. In effect said cam represents a predetermined functional relation between the speed of the train and the distance traveled thereby, this functional relation being based upon the braking curve of said train for a given stretch of track. The effective action of the cam 69 takes place along the path of movement 50 of its follower, namely the roller 77 at the upper end of the floating lever 76. The manner in which the cam 69 cooperates with the speed indicator SI to control the speed of the vehicle will be more fully explained 55 hereinafter in the description of the operation. In this connection it should be understood that while the shape of the cam 69 shown in the drawing illustrates in general the shape of a cam which may be used

in practice, no attempt has been made to 65 show this cam precisely correct in shape.

Operation.

The parts of the speed control apparatus are shown in Fig. 1 in the position which 70 they assume when traffic conditions are such that the train may travel at unlimited speed, there being, however, a limitation upon the maximum speed which the train may attain at any time, as explained hereinafter. 75 When the parts are in this position, which may be termed the normal position, the speed control relay SC is normally energized by a circuit which may be traced as follows: commencing at one terminal of the 80 battery A, conductor 121, coil SC, conductors 122 and 123, armature 111 of said coil in its upper position, conductor 124, contact piece 10, contact spring 9, and conductors 125 and 126 back to the battery A. 85

The speed control relay SC is governed by the pick-up relay P and said relay P is included in a partial circuit terminating at the contact shoe 5, and at the axle 3 of the vehicle, said partial circuit including conductors 127 and 128. When the pick-up relay P is energized in the manner herein-after explained and its armature 113 is raised, another circuit for energizing the speed control relay SC is established and 90 may be traced as follows: commencing at one terminal of the battery A, conductor 121, relay SC, conductors 122 and 129, armature 113, of the relay P in its upper position, and conductors 130 and 126 back to the 100 battery A.

With the speed control relay SC energized and the armature 112 in its upper position, the cam control magnet C is energized by a circuit which may be traced as 105 follows: commencing at one terminal of the battery B, conductors 131 and 132, armature 112 of the relay SC in its upper position, conductors 133 and 134, coils 57 of the cam control magnet C, and conductors 135 and 110 136 back to the battery B.

The solenoid 117 of the slow acting circuit controller K is also energized at this time by a circuit which may be traced as follows: commencing at one terminal of the 115 battery B, conductors 131 and 132, armature 112 of the relay SC in its upper position, conductors 133 and 137, solenoid 117 and conductors 138 and 136 to the battery B.

The brake controlling solenoid E is also 120 energized at this time by a circuit which may be traced as follows: commencing at one terminal of the battery B, conductors 131 and 139, solenoid E, conductor 140, contact springs 91 and 86, conductors 141 and 142, 125 contact spring 116, contact disk 115, contact spring 116 and conductors 143, 144 and 136 back to the battery B.

There is another circuit for energizing the brake controlling solenoid E, which is closed when the cam-shaft 66 has been moved from its initial position through a small angle so that the arm 70 secured to said cam-shaft has caused the movement of the angle lever L in one direction or the other, it being apparent from the drawing that by this movement of the angle lever L, a shunt path around the co-operating contacts of the slow acting circuit controller K is established, so that the solenoid E may be energized after the cam-shaft has moved through a small angle, independently of the slow acting circuit controller K, by a circuit which may be traced as follows: commencing at one terminal of the battery B, conductors 131 and 139, solenoid E, conductor 140, contact fingers 91 and 86, conductor 141, arm 73 of the angle lever L, one of the contact strips 74, along either conductor 145 or 146 to conductor 147, and thence by conductors 144 and 136 back to battery B.

25 *Maximum speed limitation.*

Referring to Fig. 1, which shows the parts of the speed control system in the normal position, the actual speed of the vehicle at any instant is indicated by the movement of the arm 75, since this arm is connected to the shaft 30, which in turn is connected by the arm 31 to the speed indicator SI. The lower end of the floating lever 76 is connected to the arm 75, so that the lower end of said floating lever is caused to assume different positions according to the actual speed of the vehicle at that particular instant. Fig. 1 shows the arm 75 and the motor end of the floating lever 76 in the position corresponding to zero speed and as the speed of the vehicle increases, said lower end of the floating lever assumes positions more and more to the left of the position shown; and it can be seen that if the cam 69 remains stationary so that the upper end of the lever 76 also remains stationary, the speed of the vehicle cannot exceed a certain speed without moving the floating lever 76 so far to the left as to pull the link 78 and rock the contact sector 80 so far that the notch 92 in the edge of said contact sector is brought opposite to the roller 90, thereby permitting the contact finger 86 to move away from the contact finger 91 and interrupt both of the circuits hereinbefore traced for normally energizing the brake controlling solenoid E. Obviously, when the solenoid E is deenergized, the spring 110 opens the valve 109 and causes an automatic application of the brakes by venting the train pipe 106.

By reason of this construction and arrangement of parts the brakes are automatically applied in case the vehicle at any time exceeds the predetermined maximum speed determined by the shape of the cam 69. It

should be understood that in addition to the automatic application of the brakes, there is preferably employed a warning signal, as shown and fully explained in my above mentioned prior application; but since the use of this warning signal and other features in conjunction with the speed control system illustrated, does not modify the action of the parts constituting the present invention, this warning signal and these other features have not been illustrated.

When traffic conditions are such that a train may proceed by a ramp, such as the ramp R, and may travel through the block protected by that ramp at any speed less than the predetermined maximum speed, that is, in case traffic conditions are such that a proceed signal will be displayed to the operator of the train, the switch 15 will be closed and a difference of potential will exist between the track rail 1 and the ramp R. As the vehicle reaches the ramp R and its contact shoe 5 engages said ramp, said contact shoe is raised sufficiently to separate the contact spring 9 from the contact finger 10, thereby interrupting the normally closed circuit for energizing the speed control relay SC. At the same time the partial circuit of the vehicle including the pick-up relay P is connected to the partial circuit associated with the ramp R, so that current is supplied to the relay P from the transformer T, the complete circuit for energizing the relay P being as follows: commencing at the ramp R, contact shoe 5, conductor 127, relay 100 P, conductor 128, axle 3, wheel 2, track rail 1, conductor 13, secondary 12 of the transformer T, conductor 14, switch 15 in its closed position, and conductor 16 back to the ramp R.

In this way, although one circuit for energizing the speed control relay SC is automatically broken by the engagement of the contact shoe 5 with the ramp R, the other circuit for said relay governed by the relay 110 P is closed, so that the armatures of said speed control relay remain in the upper position and hold the parts of the speed control apparatus in the normal position. It should be noted that while the contact shoe 5 is in engagement with the ramp R and so long as the normally closed circuit for energizing the speed control relay SC is broken at said contact shoe, the pick-up relay P is maintained energized, and that when the contact shoe leaves engagement with said ramp, the circuit for normally energizing the relay SC is established before the other circuit controlled by the relay P is broken.

In case traffic conditions are such that the train approaching a ramp, such as the ramp R, should so control its speed as to be brought to a stop or to a predetermined low speed by the time it reaches the end of the block protected by said ramp R, the switch 130

15 will be in its open position and no difference of potential will exist between the ramp R and the track rail 1. Under these conditions as the vehicle passes the ramp R and 5 its contact shoe 5 engages therewith, the normally closed circuit for energizing the speed control relay SC is interrupted in the same way as hereinbefore explained; but, since the switch 15 is open, the relay P is not 10 energized, and the relay SC is cut off from all current supply and its armatures drop. The dropping of the armature 111 opens a break in the normally closed circuit for the relay SC, so that after the contact shoe 5 15 leaves engagement with the ramp R, although one break in the circuit for normally energizing the relay SC is closed at the contact shoe, nevertheless this circuit remains broken at the armature 111, thereby keeping 20 the armatures of the relay SC in the lower position until the relay SC is again energized by the relay P when the vehicle passes a ramp between which and the track rail 1 a difference of potential exists. The dropping 25 of the armature 112 of the relay SC interrupts the circuits hereinbefore traced for energizing the cam control magnet C and the solenoid 117 of the slow acting circuit controller K. When the cam control magnet C 30 is deenergized, the spring 64 pushes the rod 62 upward, and raises the lever 52 so as to bring the gear 55 into mesh with the gear 67, whereupon the cam-shaft 66 is connected to the axle 3 of the vehicle and commences to 35 turn, in one direction or the other, depending upon the direction of the movement of the vehicle, gradually and exactly in correspondence with the distance traveled by the vehicle. Upon the deenergization of the 40 solenoid 117, the plunger 114 commences to move downward, but, as explained hereinbefore, a certain time must elapse before said plunger has moved far enough downward to break the connection between the contact disk 45 115 and the contact spring 116. Under normal conditions, when the gearing connecting the wheel 2 of the vehicle with the cam shaft 66 is intact and operating properly, the cam shaft 66 moves through a small angle sufficient to operate the angle lever L by the arm 50 70 to close the shunt circuit, hereinbefore traced, before the time above mentioned required for the operation of the circuit controller K will elapse, thereby maintaining 55 the solenoid E energized. In case, however, some part of the gearing connecting the cam shaft 66 with the wheel 2 is broken or deranged in any way so that said cam-shaft does not commence to move upon the deenergization of the cam control magnet C, the angle lever L will remain in the position 60 shown in Fig. 1, and after the elapse of time required for the circuit controller K to operate, the contact disk 115 will break electrical 65 contact with contact springs 116 and inter-

rupt the only path for current to flow to the brake controlling solenoid E whereupon said solenoid E will be deenergized and the automatic application of the brakes occur.

As pointed out hereinbefore, the lower end 70 of the floating lever 76 assumes different positions more and more to the left of the position shown in Fig. 1, according to the actual speed of the vehicle at that instant; and as the cam-shaft 66 and the cam 69 is turned, 75 the upper end of said floating lever is moved toward the left further and further as the train progresses at a rate depending upon the shape of the cam 69. The cam 69 is so shaped that as the vehicle progresses the 80 upper end of the floating lever 76 assumes different positions more to the left of that shown in Fig. 1, so as to correspond to the permissive speed of the vehicle at each point in its travel, determined by the braking 85 curve of the vehicle for the particular stretch of track over which the vehicle is then traveling. If it happens, and this is usually the case under ordinary conditions, that the vehicle as it first passes the ramp R and when 90 the cam control magnet C is first deenergized, is traveling at a comparative high rate of speed, nearly as great as the maximum permissive speed, the lower end of the floating lever 76 will be moved by the arm 75 to a 95 position such that the contact sector 80 is rocked downward to a position where the shoulder 92 is only a short distance from the roller 90. As the vehicle progresses and the cam 69 moves the upper end of the floating 100 lever 76 more to the left, it is apparent that the lower end of said floating lever 76 must be moved to a corresponding extent to the right in order to prevent a further movement of the link 78 to the left far enough to bring 105 the shoulder 92 in the edge of the contact sector 80 opposite to the roller 90 and cause an automatic application of the brakes; or, in other words, the actual speed of the vehicle must decrease at the same rate as the permissive speed for the vehicle, determined by the cam 69, decreases, in order to prevent an 110 automatic application of the brakes.

Other features of the automatic control of the speed of a train by the mechanism shown 115 in Fig. 1, are pointed out more at length in my prior application above mentioned; but since an understanding of these features is not necessary for a clear understanding of the important features embodying this invention, further explanation is deemed unnecessary.

Referring to the important features embodying this invention, it is apparent that the integrity of the gearing connecting the 125 wheel 2 of the vehicle with the cam-shaft 66 is checked at each operation of the speed control apparatus and any failure of this gearing is immediately detected and manifested by the automatic application of the brakes. 130

It is obvious, however, that the failure of the gearing may be manifested in other ways, if desired, by causing operation of some suitable appliance which may be generally termed a safety appliance; and other changes in the particular construction shown and described may be readily made by those skilled in the art without departing from my invention.

10 Although I have particularly described the construction of one physical embodiment of my invention, and explained the operation and principle thereof; nevertheless, I desire to have it understood that the form selected 15 is merely illustrative, but does not exhaust the possible physical embodiments of the idea of means underlying my invention.

What I claim as new and desire to secure by Letters Patent of the United States, is:

20 1. In a system for automatically controlling railway trains, in combination: means for controlling the movement of a vehicle adapted to be connected at times to a pair of wheels thereof; a normally open circuit controller governed by said means and closed after a small movement thereof: a normally closed slow acting circuit controller; means for simultaneously controlling said means and said slow acting circuit controller; a circuit controlled jointly by said circuit controllers arranged in multiple; and traffic protecting means governed by said circuit.

25 2. In a system for automatically controlling railway trains, in combination: a vehicle and a track therefor; means for determining the actual speed of the vehicle; a cam for establishing the permissive speed for said vehicle; means governed jointly by said first means and by said cam for controlling the 30 movement of the vehicle; gearing adapted to operatively connect said cam at times to a pair of wheels of the vehicle; a device for controlling said cam; a circuit on the vehicle for governing the movement thereof; means for opening said circuit after the lapse of a 35 predetermined time subsequent to the operation of said device; and means governed by the movement of said cam for closing said circuit independently of said last mentioned 40 means.

45 3. In a system for automatically controlling railway trains, in combination: a vehicle and a track therefor; a cam for governing the movement of the vehicle; means for operatively connecting said cam at times to a pair of wheels of the vehicle; cooperating devices carried by the vehicle and arranged along the track for controlling said means; and means for governing the movement of 50 the vehicle which is set into operation at each operation of said first mentioned means unless said cam moves.

60 4. In a system for automatically controlling railway trains, the combination with a vehicle, of automatic train control apparatus

thereon comprising a permissive speed device set into operation at control points along the track when dangerous traffic conditions exist and adapted when set into operation to change gradually during the progress of 70 the vehicle, a safety appliance for manifesting a failure of the permissive speed device to change, means tending to cause actuation of the safety appliance after partial progress of the vehicle past a control point when 75 dangerous traffic conditions exist, and means rendered effective after an initial change of said permissive speed device for preventing actuation of the safety appliance.

5. In a system for automatically controlling railway trains, the combination with a vehicle, of a permissive speed device on the vehicle adapted to be connected to the wheels thereof at control points along the track when dangerous traffic conditions exist and 80 to be moved gradually in accordance with the distance travelled by the vehicle, slow-acting means also set into operation at said control points under dangerous traffic conditions, and a safety appliance governed 85 jointly by said means and by said permissive speed device and actuated eventually by said slow-acting means unless said permissive speed device has partially moved.

6. In a system for automatically controlling railway trains, the combination with a vehicle, of automatic train control apparatus thereon comprising a permissive speed device adapted to change gradually to impose decreasing permissive speeds, a control relay 100 on the vehicle for governing the operation of said device, a safety appliance, time controlled means tending to cause operation of the safety appliance after the lapse of an interval of time and also governed by said 105 control relay simultaneously with said permissive speed device, and means controlled by said permissive speed device and acting after said device has partially changed for preventing operation of the safety appliance by said time controlled means.

7. In a system for automatically controlling railway trains, the combination with a vehicle, of automatic train control apparatus thereon comprising a permissive speed device having its operation initiated at control points along the track when dangerous traffic conditions exist and adapted to change gradually during the progress of the vehicle to impose lower permissive speeds, and 120 means including a time controlled device for automatically applying the brakes on the vehicle when said device fails to commence its change at a control point.

8. In a system for automatically controlling railway trains, the combination with a vehicle, of a permissive speed device thereon adapted when set into operation to change gradually during the progress of the vehicle so as to impose decreasing permissive speeds, 125

- slow-acting means set into operation simultaneously with the initiation of the operation of said permissive speed device and tending to apply the brakes on the vehicle 5 after a limited travel of the vehicle, and means responsive to a change of said permissive speed device from its initial condition for preventing an application of the brakes by said slow-acting means.
- 10 9. In a system for automatically controlling railway trains, the combination with a vehicle, of automatic train control apparatus thereon comprising a permissive speed device adapted to change gradually to impose decreasing permissive speeds, a normally closed circuit, time controlled means for interrupting said circuit after an interval of time, means for setting the said permissive speed device and said time controlled 15 means into operation at control points along the track when dangerous traffic conditions exist, and means rendered effective by a partial change of said permissive speed device for maintaining said circuit closed independently of said time controlled means.
- 20 10. In a system for automatically controlling railway trains, the combination with a vehicle, of a permissive speed cam having a tendency to assume an initial position, means adapted when set into operation to move said cam gradually against the opposition of said tendency so as to impose lower permissive speeds, a control relay for governing said means, a member also controlled 25 by said relay and movable to a final position independently of said cam, and a safety appliance jointly responsive to the movement of the cam from its initial position and to the movement of said member to its final 30 position, said appliance being rendered active when said member assumes its final position unless the cam has moved from its initial position.
- 35 11. In a system for automatically controlling railway trains, the combination with a vehicle, of a speed responsive device governed by the speed of the vehicle, a permissive speed device set into operation at control points along the track under dangerous 40 traffic conditions and adapted to change gradually during the progress of the vehicle so as to impose decreasing permissive speeds, a brake setting apparatus governed jointly by said speed responsive device and said permissive speed device and acting to automatically apply the brakes on the vehicle 45 when its actual speed exceeds the prescribed permissive speed, slow-acting means set into operation at the same time as said permissive speed device and adapted to change gradually to a final condition independently of said permissive speed device, said slow-acting means in its final condition acting to cause operation of said brake setting apparatus, and means responsive to a partial 50 change of said permissive speed device for preventing the operation of said brake setting apparatus by said slow-acting means.
- 55 12. In a system for automatically controlling railway trains, the combination with a vehicle, of a speed responsive device thereon governed in accordance with the actual speed of the vehicle, a permissive speed device adapted to impose varying permissive speeds during the progress of the vehicle, 55 a brake setting apparatus controlled jointly by said speed responsive device and said permissive speed device and operated when the actual speed of the vehicle exceeds the prescribed permissive speed, and means subjected to the same controlling influence as said permissive speed device for disclosing a failure of said permissive speed device to act after a limited travel of the vehicle.
- 60 13. In a system for automatically controlling railway trains, the combination with a vehicle, of a permissive speed device thereon adapted to change in accordance with the distance traveled by the vehicle, time controlled mechanism on the vehicle, a control 65 relay governed at control points along the track in accordance with traffic conditions for simultaneously initiating the operation of said permissive speed device and said time controlled mechanism; and a safety appliance governed jointly by the permissive speed device and the time controlled mechanism.
- 70 14. In a system for automatically controlling railway trains, the combination with a vehicle, of automatic train control apparatus thereon having its operation initiated at control points along the track when dangerous traffic conditions exist, and automatic checking means subjected to the same controlling influence as said apparatus and actuated after the lapse of an interval of time unless said apparatus has operated.
- 75 15. In a system for automatically controlling railway trains, the combination with a vehicle, of a time controlled device thereon tending to apply the brakes after the lapse of an interval of time, means for setting said device into operation at control points along the track under dangerous traffic conditions, 80 automatic train control apparatus on the vehicle, and means for preventing the application of the brakes by said time controlled device so long as said apparatus is active to control the vehicle.
- 85 16. In a system for automatically controlling railway trains, the combination with a vehicle, of a permissive speed device thereon adapted to change gradually during the progress of the vehicle so as to impose decreasing permissive speeds, means operated by a change of said device from its initial condition, and a safety appliance controlled by said means.
- 90 17. In a system for automatically control- 85

- 130

- ling railway trains, the combination with a vehicle, of a permissive speed device thereon adapted to change gradually during the progress of the vehicle so as to impose decreasing permissive speeds, means for initiating the operation of said device, and a safety appliance rendered effective each time the operation of said device is initiated unless it commences to change.
18. In a system for automatically controlling railway trains, the combination with a vehicle, of automatic train control apparatus thereon for restricting the speed of the vehicle at different points in its travel when dangerous traffic conditions exist, said apparatus comprising a movable element adapted to be moved in accordance with the travel of the vehicle, and means subjected to the same controlling influence as said element for disclosing when said element fails to move.
19. In a system for automatically controlling railway trains, the combination with a vehicle, of automatic train control apparatus thereon comprising a movable element biased to an initial position, means rendered active by a partial movement of said element from its initial position, control devices for initiating the movement of said element when dangerous traffic conditions exist, and means governed by said control devices for disclosing when said means is not active.
20. In a system for automatically controlling railway trains, the combination with a vehicle, of automatic train control apparatus thereon adapted to be placed in an active controlling condition to govern the movement of the vehicle at different control points along the track, control devices partly on the vehicle and partly along the track for placing said apparatus in its active controlling condition, and checking means also governed by said control devices and including a safety appliance actuated automatically when said apparatus fails to respond and assume its active controlling condition.
21. In a system for automatically controlling railway trains, the combination with a vehicle, of a control relay thereon, means partly on the vehicle and partly on the track for governing said control relay in accordance with traffic conditions, train control apparatus having its operation governed by said relay, and checking means also controlled by said relay and automatically assuming its active condition when said apparatus fails to operate.
22. In a system for automatically controlling railway trains, the combination with a vehicle, of automatic train control apparatus thereon comprising two separate devices both subjected to the same controlling influence and each adapted to change gradually to an ultimate condition independently of the other, and a safety appliance controlled by said devices and operated when one of said devices attains its ultimate condition before the other commences its change, whereby the operation of one device is checked by the other.
23. In an automatic train control system, automatic train control apparatus for railway vehicles, slow-acting means subjected to the same controlling influence as said apparatus, and checking means actuated automatically when the train control apparatus fails to operate before said slow-acting means.
24. In an automatic train control system, automatic train control apparatus for railway vehicles, and means subjected to the same controlling influence as said apparatus for detecting a failure thereof to become active when controlled to do so, the action of said means being delayed sufficiently to permit the train control apparatus becoming active when operating properly.
25. Automatic train control apparatus for railway vehicles including a permissive speed device adapted to change from a normal initial condition, normally inactive means operated after said element has commenced its change from said initial condition, and means including said normally inactive means and a device subjected to the same controlling influence as said element for detecting a failure of said element to commence its change when controlled to do so.
26. Car equipment for automatic train control systems comprising, a normally energized slow acting device tending to change to an ultimate condition, brake control means actuated when said device attains its ultimate condition, a normally closed circuit for energizing said device, train control apparatus, and means adapted to be conditioned from the trackway for interrupting said circuit and for governing the operation of said apparatus.
27. Car equipment for automatic train control systems comprising, a brake control device, a normally closed circuit including said device, time controlled means tending to change from an initial condition to an ultimate condition and acting when in its ultimate condition to interrupt said circuit, means for normally maintaining the time controlled means in its initial condition, train control apparatus and a relay controlled from the trackway for governing the operation of said apparatus and for initiating the change of said time controlled means.
28. Car equipment for automatic train control systems comprising, time controlled means effective to cause an automatic brake application after a time interval, other brake control apparatus adapted when oper-

- ating to prevent such brake application by the time controlled means and means governed from the trackway for simultaneously initiating the operation of the time controlled means and said other brake control apparatus. 5
29. Car equipment for automatic train control systems comprising, a brake control appliance, a governing circuit for said appliance including two multiple branches, automatic train control apparatus for actuating said appliance, a separate device subjected to the same controlling influence as said apparatus for breaking one of the multiple branches, and means for closing the other branch when said apparatus is acting. 10
30. Car equipment for automatic train control systems comprising, train control apparatus, a separate device set into operation at the same time as said apparatus, a brake control appliance, and an energizing circuit for said appliance having two branches in multiple, said apparatus when operating closing one branch, and said device when operated opening the other branch. 15
31. Car equipment for automatic train control systems comprising a brake control appliance, two circuit controllers each effective when closed to maintain said appliance inactive, train control apparatus including means for closing one circuit controller when the apparatus is operating, and means separate from said apparatus but subjected to the same governing influence for opening the other circuit controller when the apparatus is conditioned for operation. 20
32. Car equipment for automatic train control systems comprising train control apparatus adapted to be conditioned for operation from the trackway, and automatic means including a device subjected to the same governing influence as said apparatus but operable independently thereof for determining when said apparatus fails to operate when conditioned for operation from the trackway. 25
33. Car equipment for automatic train control systems comprising, normally inactive train control apparatus including a movable element shifted when said apparatus is not in its active controlling condition, and means subjected to the same controlling influence as said apparatus for causing an automatic brake application when said element fails to shift. 30
34. In a train control system, speed governed brake control apparatus on a vehicle, means partly on the vehicle and partly on the track for controlling operation of said apparatus, and means for detecting failure of said apparatus to operate in response to the control thereof from the trackway, said means including the device subjected to the
- same controlling influence as said apparatus but operable independently thereof. 35. In a train control system, train control apparatus on a vehicle, control means partly on the vehicle and partly on the track for governing said apparatus in accordance with traffic conditions, and automatic means governed by said control means and set into operation at the same time as said apparatus for causing an automatic brake application when the apparatus fails to operate. 70
36. In a train control system, train control apparatus on a vehicle, control means for said apparatus partly on the vehicle and partly on the track, slow acting means governed by the control means and set into operation at the same time as the said apparatus, said slow acting means when operated causing an automatic brake application after an interval of delay, and automatic means for preventing such brake application by the action of the slow acting means when the train control apparatus is operating. 75
37. In a train control system, train control apparatus on a vehicle, a detecting device set into operation at the same time as the apparatus, and operable independently thereof, and automatic means responsive to the joint control of the apparatus and the detecting device for causing a brake application when the apparatus fails to operate 80 when conditioned for operation from the trackway. 85
38. In a train control system, train control apparatus on a vehicle, changeable means assuming a changed condition when said apparatus operates, a separate device operable independently of said apparatus and set into operation at the same time, a brake control appliance, and means for actuating said appliance upon operation of the separate device when said changeable means is not in its changed condition. 90
39. In a train control system, car-carried brake control apparatus adapted to be conditioned for operation from the trackway, a detecting device operable independently of said apparatus and conditioned for operation from the trackway at the same time, said detecting device tending to cause a brake application after an interval of delay, 100 and means automatically rendered inactive by the operation of said apparatus for preventing such brake application by said detecting device. 105
40. In a train control system, speed governed brake control apparatus on a vehicle, means partly on the vehicle and partly on the track for governing the operation of said apparatus in accordance with traffic conditions, slow acting means operable independently of said apparatus but governed by said means in the same way, said slow acting means when operated tending to cause an 110
- 115
- 120
- 125

automatic brake application, and normally inactive means automatically rendered effective upon operation of said apparatus for preventing such automatic brake application.

41. In a train control system, control equipment comprising, a brake control appliance, speed governed mechanism including a changeable device adapted when in its changed position to maintain said appliance inactive subject to the operation thereof at excessive speeds, and biased slow acting means having its operation automatically initiated at the same time as said apparatus and operable independently thereof, said slow acting means tending to operate the brake control appliance after an interval of delay.

42. In a train control system, car-carried apparatus for governing the movement of the car and having its operation automatically governed from the trackway in accordance with traffic conditions, said apparatus including normally inactive means changed when said apparatus assumes its active operating condition, and means whereby the brakes of the car are automatically applied upon failure of said means to change when

the apparatus is conditioned for operation from the trackway under dangerous traffic conditions.

43. In a train control system the combination with speed governed brake control apparatus on a vehicle, of automatic means for manifesting the failure of said apparatus to operate means for detecting failure in the operation of train control apparatus on railway vehicles comprising, a brake governing device subjected to the same controlling influence as said apparatus but operable independently thereof.

44. In a system for governing the movement of railway vehicles, apparatus on a vehicle intermittently controlled from the trackway in accordance with traffic conditions, and automatic means for detecting failure of said apparatus to respond to the trackway control.

45. In a train control system, the combination with a safety appliance on a vehicle, of independently operable train control apparatus and detecting means subjected to the same controlling influence from the trackway for exerting opposite governing influences upon said appliance.

WINTHROP K. HOWE.
